ELMER G. MUNZ, OF DETROIT, MICHIGAN

SPRINKLER

Application filed May 26, 1930. Serial No. 455,869.

This invention relates generally to sprinklers for lawns and the like and refers more particularly to those applicable to underground piping systems.

5 One of the essential objects of the invention is to provide an efficient sprinkler in which a film of water engages a plurality of inclined blades or fins on a rotatable nozzle and causes the latter to rotate.

10 Another object is to provide a sprinkler in which the blades are arranged at such an angle with respect to the film of water that the speed of rotation of the nozzle is predetermined.

15 Another object is to provide a sprinkler in which the nozzle is supported axially on a stem and is movable longitudinally thereof successively upwardly and downwardly with respect to a portion thereof depending upon 20 the pressure of water within the nozzle above and below the said portion, so that the nozzle will be hydraulically balanced and will substantially float while rotating.

25 Another object is to provide a simple and compact rotary or revolving sprinkler having a radial discharge adapted to cover the greatest possible area with a minimum amount of water.

30 Another object is to provide an efficient sprinkler in which all of the operating parts are within the sprinkler itself so that they are kept clean and lubricated by the water and protected from dirt when they are installed in the ground as permanent fixtures.

35 With the above and other objects in view the invention consists of certain novel features of construction, combinations and arrangements of parts that will be hereinafter more fully described and particularly pointed out in the appended claims.

In the accompanying drawing:

Figure 1 is a vertical sectional view through a sprinkler embodying my invention and showing the parts in operative sprinkling position;

Figure 2 is a view similar to Figure 1 but showing the parts in inactive position;

Figure 3 is a cross sectional view taken on the line 3—3 of Figure 1.

50 Referring now to the drawing, A is the

casing; B is the rotatable body or nozzle; and C is the stem for the body of a sprinkler embodying my invention. As shown, the casing A has a tubular portion 1 threaded upon the upper end of a water supply pipe D in the ground and has an upwardly opening cup-shaped portion 2 provided at its upper end with a lateral flange 3 that is substantially flush with the upper surface of the ground. The body or nozzle B is supported axially on the stem C and is movable longitudinally of the cup-shaped portion 2 of the casing. Preferably the body B has two sections E and F respectively threadedly engaging each other. The lower section E has a base 4 and a cylindrical wall portion 5. The base 4 also has an axial opening 6, an annular recess 7 in its upper face about the opening 6, and a series of inclined blades or fins 8 extending between and connecting into the base 4 and cylindrical wall portion 5. The upper section F has a top portion 10, an inverted cup-shaped portion 11 and an intermediate web portion 12. As shown, the top portion 10 is flat and is adapted to seat in an annular recess 13 in the flange 3 of the casing and to cooperate with the latter to enclose the other parts when the body is in lowered position; the web 12 is at the center of the top portion; and the cup-shaped portion 11 has the downwardly and outwardly flaring wall portion 15 and the depending cylindrical wall portion 16. Preferably the flaring wall portion 15 has openings 17 therein that incline upwardly relative to the axis of the rotatable body B, while the cylindrical wall portion 16 has internal threads engaging external threads on the cylindrical wall portion 5 of the lower section. The stem C is tubular in form and extends through the bases 18 and 4 respectively of the cup-shaped portion 2 of the casing and of the body B. Preferably the stem is provided at its lower end with a nut 19 that is engageable with the lower face 20 of the base and is provided at its upper end with a series of openings 22 and a flat circular top or head 23.

In use the body B, stem C and nut 19 as a unit are movable vertically within the cas-

ing. When the water supply to the pipe D is turned off the body B, stem C and nut 19 are in lowered position within the casing (see Figure 2), and the top 10 seats within the annular groove 13. However, when the water supply to the pipe D is turned on the water will rise in the tubular part of the casing 1 against the lower face of the nut 19 and will cause the nut, stem C and body 10 B to rise until the nut 19 engages the lower face 20 of the cup-shaped base (Figure 1) whereupon water rising in the stem C will flow laterally through the openings 22 in the stem to the blades or fins 8 and will cause 15 the nozzle B to rotate. As water is discharged from the stem C through the openings 22 into the body B, the pressure of water forces the body B upwardly until the base 4 contacts with the head 23. The recess 7 20 is then closed by the top 23, consequently water discharged from the openings 22 will build up a pressure in the recess 7. Since the supply of water into the body above the head 23 has thus been cut off and the water 25 has been discharging through the openings 17, the pressure in this upper portion has decreased accordingly. As a result the water in the recess 7 builds up to a pressure greater than that above the head 23, consequently 30 the body B is forced downwardly, permitting water to escape from the recess 7 upwardly about the head 23 into the upper portion of the body B. This will again force the body B upwardly until the pressures 35 above and below the head 23 are in proper ratio to balance the head hydraulically. In other words, the body will come to rest in a position which will allow enough water to escape from below the head 23 and flow to 40 the upper portion F of the body to cause the latter to be balanced. The water flows in a thin film from the recess 7 past the head 23 and prevents any contact between these two members and eliminates friction at this point. 45 Since the body B is provided with fins or blades 8, it is apparent that this film of water contacting therewith will cause positive rotation of the body B. The angle of the blades with respect to the film of water will determine the speed of rotation of the body B. It is obvious that the speed of this device might also be controlled by a set of brakes similar to those shown in my companion case 50 #455,868.

55 What I claim as my invention is:

1. In a sprinkler, a stem having a head, and fluid discharge means at one side of the head, and a nozzle mounted for both rotary and longitudinal movement on the stem, receiving the head, and having fins engageable by the fluid from the discharge means to cause the nozzle to rotate, and the nozzle being constructed and arranged relative to the head whereby the fluid engageable with the fins will be in the form of a thin film.

2. In a sprinkler, a stem having a head constituting a baffle and being provided beneath the head with water outlets, and a nozzle rotatably mounted on the stem and enclosing the head, means in said nozzle coacting with 70 said head to form two water chambers on opposite sides thereof whereby water from the outlets is received in one of said water chambers and flows around said head into the other water chamber, said nozzle having a discharge 75 outlet in said other water chamber and being also movable longitudinally of the stem depending upon the pressure of water within the nozzle above and below the head.

3. In a sprinkler, a water supply conduit 80 having a discharge orifice, a member surrounding the end of said supply conduit rotatable about a substantially vertical axis and axially slid able, said member having a water chamber therein for receiving water from 85 said discharge orifice and having a discharge outlet, and cooperating means on said rotatable member and supply conduit respectively arranged intermediate the discharge orifice in said conduit and the discharge outlet in 90 said rotatable member for creating a back pressure whereby said rotatable member is sufficiently balanced to facilitate rotation thereof.

4. In a sprinkler, a water supply conduit 95 having a discharge orifice, a member surrounding the end of said supply conduit rotatable about a substantially vertical axis and axially slid able, said member having a water chamber therein for receiving water from 100 said discharge orifice and having a discharge outlet, and a member on said supply conduit arranged intermediate said discharge orifice in said conduit and said discharge outlet in 105 said rotatable member for throttling the water passing therebetween.

5. In a sprinkler, a water supply conduit having a discharge orifice, a member surrounding the end of said supply conduit rotatable about a substantially vertical axis and 110 axially slid able, said member having a water chamber therein for receiving water from said discharge orifice, discharge means in said rotatable member for directing substantially all of the water radially outward 115 whereby the maximum area will be sprinkled, and cooperating means on said rotatable member and supply conduit respectively arranged intermediate the discharge orifice in 120 said conduit and the discharge means in said rotatable member for creating a back pressure whereby said rotatable member is sufficiently balanced to facilitate rotation thereof.

6. In a sprinkler, a stationary casing, a hollow stem vertically slid able in said casing and 125 having an enlarged head at the upper end thereof, said stem being provided with discharge orifices below said head, a hollow member surrounding said head and said discharge orifices, said member being rotatable 130

and axially slidable on said stem, discharge means on said rotatable member for projecting substantially all of the water radially outward whereby the maximum area may be 5 sprinkled, said rotatable member having a portion adapted to contact with said head intermediate said discharge orifices in said stem and said discharge means in said rotatable member whereby a back pressure on said rotatable member is obtained.

7. In a sprinkler, a stationary casing, a hollow stem vertically slidable in said casing and having an enlarged head at the upper end thereof, said stem being provided with discharge orifices below said head, a hollow member surrounding said head and said discharge orifices, said member being rotatable and axially slid able on said stem, discharge means on said rotatable member for projecting substantially all of the water radially outward whereby the maximum area may be 15 20 sprinkled, said rotatable member having a

portion adapted to contact with said head intermediate said discharge orifices in said stem and said discharge means in said rotatable member whereby a back pressure on said rotatable member is obtained, and inclined 70 blades on said rotatable member in the path of the water from said discharge orifices in said stem.

8. In a sprinkler, a non-rotatable member provided with means for discharging water 75 radially, a rotatable member surrounding the discharge end of said stationary member and having a closed water chamber therein, means on said rotatable member in the path of said radial discharge for rotating said member 80 from the impact of the water, a discharge outlet in said rotatable member, and means intermediate said radial discharge means and said discharge outlet for creating a back pressure whereby said rotating member is hy- 85 draulically balanced.
